UNITED STATES PATENT OFFICE.

GUSTAV BERNHARD PETSCHE, OF PHILADELPHIA, PENNSYLVANIA, AS-SIGNOR TO THE SOUTHWARK FOUNDRY & MACHINE COMPANY, OF SAME PLACE.

AIR-COMPRESSING OR BLOWING ENGINE.

SPECIFICATION forming part of Letters Patent No. 669,853, dated March 12, 1901.

Original application filed July 31, 1897, Serial No. 646,636. Divided and this application filed February 1, 1900. Serial No. 3,614. (No model.)

To all whom it may concern:

Be it known that I, GUSTAV BERNHARD PETSCHE, a subject of the Emperor of Germany, residing in the city and county of Philadelphia, in the State of Pennsylvania, have invented a certain new and useful Improvement in Air-Compressing or Blowing Engines, of which the following is a true and exact description, reference being had to the accompanying drawings, which form a part thereof.

My invention relates to air-compressing or blowing engines, and has for its object to provide efficient means for actuating and regulating the throw of the admission-valves in such engines.

The nature of my improvement will be best understood as described in connection with the drawings in which it is illustrated, and in which—

Figure 1 is a side elevation of a blowing-engine provided with my improvement, and Fig. 2 a diagrammatic drawing showing the manner in which my device operates.

A indicates the framing of the engine; B, the steam-cylinder, the upper portion being cut away to provide for showing the other parts of the engine on a larger scale.

C is the main shaft of the engine, driven from the steam-cylinder in any usual and convenient manner.

E is the compressing-cylinder of the engine, E' E' indicating the receivers, into which the delivery-valves open at the opposite ends of the cylinder.

G G indicate the valve-stems connected with the admission-valves of the engine. As shown, they have attached to their outer ends cam-slotted slides G', moving in guideways, (indicated at G².)

G³ G³ indicate bell-crank levers pivoted on the guideways G², having at one end cam-rollers g³, which move in the slot-cams, and having their other ends connected to a reciprocating rod G⁴, which rod connects through a pivoted lever G⁵ with another reciprocating rod G⁶, which at its lower end is connected at Q³ with a swinging link Q², one end of which

is pivotally connected with an adjustable slide Q, moving in a guideway Q⁵ and adjustable by means of a set-screw Q'. The other end of the swinging link Q² is pivotally connected at q² with another swinging link Q⁴, which link is also pivotally connected with an arm P², extending out from an eccentric-ring P^X, which ring extends around an eccentric P, secured to the shaft C, and has on its opposite side another arm P', which arm is pivotally connected at P³ in the slide P⁴, making up a familiar link-motion, and, as shown, the arm P' is also connected by a link O³ with a slide O, moving in a guideway N and having attached to it a rod O², which, as described in my former application, Serial No. 646,636, filed July 31, 1897, can be conveniently used for actuating the valves of the steam-cylinder. This, however, forms no part of my present invention, which is solely concerned with the actuation of the air-admission valves irrespective of the means used for actuating the steam-valves, my air-admission-valve-actuating mechanism in its combination with the steam-valve-actuating mechanism being claimed in my said former application, of which the present case is a division.

While I have shown the rod G⁶ connected to link Q² near its connection with slide Q, it will be obvious that the kind of motion desired will be secured by connecting rod G⁶ with any intermediate point on either of the links Q² or Q⁴, the section of the point of attachment being a mere matter of mechanical skill, depending on the amount of motion desired.

In the diagram Fig. 2 I have shown the effect of three different adjustments of the slide Q, from which it will readily be seen how said adjustments will necessarily affect the movement of the admission-valves, and I will further say that the nature of the connecting mechanism by which the movement of the swinging links is communicated to the valves can be varied without departure from my invention.

Having now described my invention, what

I claim as new, and desire to secure by Letters Patent, is—

In an air-compressing engine the combination with a positively-driven eccentric P and a link $P' P^2$ actuated thereby of a slide P^4 in which the arm P' of the link is pivoted, a slide Q arranged to be adjusted toward and away from the link $P' P^2$, a pair of links Q^2 Q^4 pivotally connected together and connected also as shown with the arm P^2 of the link

$P' P^2$ and with the slide Q and a valve-actuating connection extending from an intermediate point on said links to the air-admission - valve mechanism of the compressing-cylinder.

GUSTAV BERNHARD PETSCHE.
